CLAIM

The ornamental design for a thermostat housing, as shown and described.

DESCRIPTION

FIG. 1 is a top, front and right side perspective view of a thermostat housing showing my new design;

FIG. 2 is a top plan view thereof;

FIG. 3 is a front elevational view thereof;

FIG. 4 is a left side elevational view thereof, the right side elevational view being a mirror image; and,

FIG. 5 is a bottom plan view thereof.
